ATTORNEYS.

Patented Mar. 10, 1925.

UNITED STATES PATENT OFFICE.

FRANK H. NEFF, OF CLEVELAND, OHIO, ASSIGNOR TO THE ELECTRIC RAILWAY IMPROVEMENT COMPANY, OF CLEVELAND, OHIO, A CORPORATION OF OHIO.

RAIL BOND.

Application filed November 4, 1918. Serial No. 261,129.

To all whom it may concern:

Be it known that I, FRANK H. NEFF, a citizen of the United States, and a resident of Cleveland, county of Cuyahoga and State of Ohio, have invented a new and useful Improvement in Rail Bonds, of which the following is a specification, the principle of the invention being herein explained and the best mode in which I have contemplated applying that principle so as to distinguish it from other inventions.

The advantage of providing the terminals of a rail bond, where the latter, as is usually the case, is made of copper or other metal having a relatively low fusing point when compared with that of the rail, with a plate or jacket other than the metal of the bond, for example a plate or jacket of steel, has heretofore been recognized. This advantage is more especially in evidence where it is desired to attach the bond terminal to the rail by fused metal from an arc pencil, in the fashion described, for example, in United States Patent No. 1,168,753, to B. F. Silliman, dated January 18, 1916.

One object of the present invention is to provide a plated or jacketed bond terminal that will permit the bond to be disposed at various angles to the face of the rail to which it is to be attached, and yet leave the necessary trough or crevice in which to deposit the fused metal from such a pencil. A further object is to select a metal for such plate or jacket that will not fuse too readily, i. e. in advance of the rail face to which the bond is thus to be attached; while still another object is so to attach the plate or jacket to the bond terminal as not to destroy the flexibility of the latter.

To the accomplishment of the foregoing and related ends, the invention, then, consists of the means hereinafter fully described and particularly pointed out in the claims, the annexed drawing and the following description setting forth in detail certain physical embodiments of the invention, which, however, constitutes but several of the various mechanical forms in which the principle of the invention may be used.

In said annexed drawing:—

Fig. 1 is a transverse section of a rail showing my improved bond in end elevation applied thereto; Fig. 2 is a view similar to Fig. 1, but showing the bond disposed in a

different position; Fig. 3 is a side elevational view of such bond and the adjacent rail ends electrically united thereby; Fig. 4 is a transverse section of the bond terminal in the course of its manufacture; Fig. 5 is a plan view of one of the electrodes employed in such manufacture; Fig. 6 is a transverse section, and Fig. 7 is a longitudinal section, of such bond as applied to the rail, the planes of such sections respectively being indicated by the lines 6—6 and 7—7, Fig. 3.

The bond shown in the several figures of the drawing is of a familiar type, consisting of a flexible stranded body 1 of copper, aluminum or like metal of high electrical conductivity, such bond having terminals 2 designed to be connected to the rails 3. Referring more especially to the form of terminal illustrated in Figs. 1, 2 and 3, it will be observed that such terminal is of triangular cross-section, the angles being approximately equal, or the triangle, in other words equilateral. The sides or faces of such terminal, at least the two upwardly directed faces, are substantially entirely covered by a plate or jacket 4 composed of a metal having a higher melting point than that of the metal whereof the bond, including such terminals, is composed. Preferably I make such plate or jacket of wrought iron, which not only has a higher melting point, (approximately 2900° F.) than the metal of the bond, but also a higher melting point than the steel of which the rail is composed. The advantage of employing such a metal will be subsequently explained.

This enclosing plate or jacket is preferably applied to the bond terminals in the shop by resistance welding, two electrodes 5 and 6 of the cross-sectional form illustrated in Fig. 6 being employed. One of these electrodes is formed on its face with a groove or depression 7 having approximately the shape and dimensions of the terminal, so as to receive such terminal which is preliminarily formed in a press at the same time that the jacket is applied thereto, a sheet 8 of braze being interposed between such jacket and the terminal proper. Such preliminarily formed terminal 105 somewhat more than fills the recess, so that when the upper electrode 6 is brought down, as shown in Fig. 4, and a heating

electric current passed from the one electrode to the other through the terminal, the exercise of further pressure will serve to compact or consolidate the stranded material of the bond, and more completely close the jacket thereon. By allowing the inner end of the terminal to protrude somewhat beyond the electrodes 5 and 6, or by other suitable expedient, the consolidation of the strands will be gradual from the extreme end of the terminal towards the end where the strands enter the jacket, as illustrated in Fig. 7, it being desirable to leave the strands, at least those in the center of the terminal, relatively free at this last mentioned point, so as not to destroy the flexibility of the bond. In other words, the outer layer of strands will be thoroughly welded to all sides of the enclosing jacket throughout the extent of the latter, but the inner strands composing the core of the terminal are consolidated, and united together only as they approach the outer extremity of the terminal.

In applying the bond to the rail, the body may be laid alongside thereof in either of the two positions illustrated in Figs. 1 and 2, and still leave a V-shaped opening or trough between the adjacent angular face 30 and the face of the rail (whether rail head, web or other portion) to which the terminal is to be attached. An arc is then sprung between a pencil 10, which is suitably connected to the source of current supply and the rail or bond. The arc causes the end of the pencil to melt away at the same time that it highly heats the adjacent faces of the jacket and rail, so that the molten metal 11, that drops from the pencil, unites homogeneously with both such jacket and rail, welding the former, and thus the bond terminal, securely to the latter.

By making the jacket 4 of wrought iron, which has a fusing temperature from 300° to 45° higher than that of the steel of which the rail is composed, the two faces which it is desired to unite may be brought practically simultaneously to the proper welding temperature, in spite of the disparity in size of the parts in question. It will be obvious that were the jacket made

of a metal having the same composition and fusing point as the metal in the rail, the difference in size of the two would be apt to cause the jacket to fuse prematurely, and thus destroy the utility of the device.

The molten metal from the pencil is used not merely to fill up the trough-space between the bond terminal and the rail, but is also allowed to overflow past the outer extremity of the terminal so as to build up a wedge-like abutment 12 contiguous to and in effect integral with such extremity, as clearly shown in Figs. 3 and 7. Such abutment serves to deflect vehicle wheels, which might otherwise, upon engaging the terminal, tend to loosen the weld, the jacket itself assisting in this, particularly in the position of the bond shown in Fig. 1.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. A rail-bond having a body and terminal, such terminal being of approximately equi-angular triangular form in cross-section so as to leave a trough-like recess between itself and the same side of the rail to which said bond is being attached in either a vertical or horizontal position of such body relatively to such rail.

2. A rail-bond having a body and terminal of copper or similar metal of relatively lower fusing point than the rail to which said bond is to be attached, said terminal being substantially enclosed in a metal jacket of higher fusing point than the material of such bond and being of approximately equi-angular triangular form in cross-section so as to leave a trough-like recess between itself and the same side of the rail to which said bond is being attached in either a vertical or horizontal position of such body relatively to such rail.

Signed by me, this 1st day of November, 1918.

FRANK H. NEFF.
